UNITED STATES PATENT OFFICE

169,479

CATALYST BATTERY CAP

Harold M. Gulick, Miami, and Cresswell E. Stedman, Coral Gables, Fla., assignors to Industrial Research, Inc., Miami, Fla., a corporation of Florida

Application December 8, 1952, Serial No. 22,596

Term of patent 14 years

(Cl. D26—6)

To all whom it may concern:

Be it known that we, Harold M. Gulick, and Cresswell E. Stedman, citizens of the United States, respectively residing at Miami and Coral Gables, in the county of Dade and State of Florida, have invented a new, original, and ornamental Design for a Catalyst Battery Cap, of which the following is a specification, reference being had to the accompanying drawing, forming a part hereof:

In the drawing:

Fig. 1 is a side elevational view of a battery cap showing our new design;

Fig. 2 is a side elevational view seen from the left hand side in Fig. 1;

Fig. 3 is a top plan view thereof; and

Fig. 4 is a bottom plan view thereof.

We claim:

The ornamental design for a catalyst battery cap, substantially as shown.

HAROLD M. GULICK.
CRESSWELL E. STEDMAN.
